US00D566282S

(12) **United States Design Patent** (10) **Patent No.:** **US D566,282 S**
Al-Ali et al. (45) **Date of Patent:** **** Apr. 8, 2008**

(54) **STAND FOR A PORTABLE PATIENT MONITOR**

(75) Inventors: **Ammar Al-Ali**, Tustin, CA (US);
Gerrick Maurer, Newport Beach, CA (US)

(73) Assignee: **Masimo Corporation**, Irvine, CA (US)

(**) Term: **14 Years**

(21) Appl. No.: **29/223,769**

(22) Filed: **Feb. 18, 2005**

(51) **LOC (8) Cl.** **24-02**

(52) **U.S. Cl.** **D24/185**

(58) **Field of Classification Search** **D24/167, D24/170, 185, 186, 232; D14/217, 434, D14/449; 361/679, 681, 686; 600/301, 600/485**

See application file for complete search history.

(57) **CLAIM**

The ornamental design for a stand for a portable patient monitor, as shown and described.

DESCRIPTION

FIG. 1 is a front top perspective view of a stand for a portable patient monitor showing our new design;

FIG. 2 is a front bottom perspective view thereof;

FIG. 3 is a top view thereof;

FIG. 4 is a bottom view thereof;

FIG. 5 is a right side view thereof, the left side being a mirror image thereof;

FIG. 6 is a front view thereof; and,

FIG. 7 is a rear view thereof.

Where utilized, phantom lining is for illustrative purposes only and does not limit or form any part of the claimed design.

The broken lines used are for illustrative purposes only and form no part of the claimed design.

1 Claim, 4 Drawing Sheets
